Primary Examiner — Wan Laymon*Assistant Examiner* — Mark Booker(74) *Attorney, Agent, or Firm* — Bodner & O'Rourke, LLP; Gerald T. Bodner; Christian P. Bodner(57) **CLAIM**

The ornamental design for a mounting device, substantially as shown and described.

DESCRIPTION

FIG. 1 is a top, front perspective view of a mounting device showing our new design;

FIG. 2 is a front elevational view thereof, a rear elevational view thereof being a mirror image of the front elevational view shown in FIG. 2;

FIG. 3 is a left elevational view thereof, a right elevational view thereof being a mirror image of the left elevational view shown in FIG. 3;

FIG. 4 is a top plan view thereof; and,

FIG. 5 is a bottom plan view thereof.
